UNITED STATES PATENT OFFICE.

FERDINAND BISCHITZ, OF NEW YORK, N. Y., ASSIGNOR TO ELEKTRA TOY & NOVELTY CO., OF NEW YORK, N. Y.

DESIGN FOR A STATUETTE OR FIGURE.

53,701.

Specification for Design.

Patented Aug. 19, 1919.

Application filed April 16, 1919. Serial No. 290,617. Term of patent 3½ years.

To all whom it may concern:

Be it known that I, FERDINAND BISCHITZ, a citizen of the United States of America, and resident of the city, county, and State of New York, have invented a certain new, original, and ornamental Design for a Statuette or Figure, of which the following is a specification, reference being had to the accompanying drawing, forming part thereof.

In the drawing, Figure 1 is a front elevation of a statuette or figure embodying my design; and

Fig. 2 is a side elevation of the same.

I claim:

The ornamental design for a statuette or figure as shown.

FERDINAND BISCHITZ.
